UNITED STATES PATENT OFFICE.

VINCENT BENDIX, OF CHICAGO, ILLINOIS.

ENGINE-STARTER.

1,258,303.

Specification of Letters Patent.

Patented Mar. 5, 1918.

Application filed August 26, 1916. Serial No. 117,093.

To all whom it may concern:

Be it known that I, VINCENT BENDIX, a citizen of the United States, residing at Chicago, in the county of Cook and State of Illinois, have invented certain new and useful Improvements in Engine-Starters, of which the following is a specification.

My invention relates to that type of engine starter exemplified in patents heretofore issued to me, for instance, Patent No. 1,172,864, dated February 22, 1916, and Patent No. 1,146,992, dated July 20, 1915, which starter is characterized by a prime mover, such as an electric motor, and a transmission or drive for transmitting the power of the motor by means of a screw shaft and pinion mounted thereon to a member of the engine to be started, such as the fly wheel thereof. This drive comprises a screw shaft, operating either directly or indirectly by the motor and a pinion screwthreaded on such shaft having longitudinal movement thereon and rotary movement therewith. My invention pertains to the construction and formation of the teeth of this pinion at the meshing end thereof, and the object thereof is to so construct such pinion teeth as to improve the meshing action thereof and prevent wear and injury on such teeth as well as on the teeth of the flywheel or other engine member.

In the drawing, Figure 1 is an elevation of a portion of the drive illustrating a pinion embodying my invention, and also showing a portion of a fly wheel, partly in section, with which the pinion meshes; Figs. 2 and 3 are detail perspective views of the end of one of the teeth of the pinion; Fig. 4 a plan view of one of the pinion teeth; and Fig. 5 an end view of a portion of the fly wheel gear.

As shown in Fig. 1, the portion of the drive herein illustrated comprises the screw-shaft 1, pinion 2 screw-threaded thereupon and the stop-nut 3 at one end of the screw-shaft. When the screw-shaft is rotated by the motor (not shown) the pinion is adapted to move to the right longitudinally of the shaft and to mesh with the teeth 4^a of the fly wheel 4, or other rotary engine member.

In the meshing operation the pinion is not

always presented to the fly-wheel teeth in accurate meshing position, that is, with the teeth of the pinion in alinement or register with the grooves or spaces between the teeth 55 of the fly-wheel, and sometimes the teeth of the pinion will abut the fly-wheel teeth end to end. In such latter case the resistance or stoppage of the longitudinal movement of the pinion will compel a longitudinal or endwise movement of the screw-shaft against the tension of the coiled spring and a slight rotary movement of the pinion on the screw-shaft until the proper alinement or register occurs between the pinion and 60 the fly-wheel teeth. Also it sometimes happens that this lack of register between the teeth for proper meshing operation is only partial, and in such event, a partial rotation of the pinion in the manner described will 65 bring about the proper register and the consequent final meshing between the pinion and the fly-wheel.

The object of my invention is to facilitate this meshing operation, and to prevent possible injury to the meshing parts, by beveling or chamfering one side only of the teeth at the meshing end thereof, and also curving and rounding the extreme ends thereof. The chamfering of the teeth is on that side 75 opposite the driving side of the teeth when they are in mesh with the fly-wheel, or in other words, the righthand side of the teeth when they are viewed from the left hand side of Fig. 1, it being understood that 80 the electric motor drives the shaft in an anti-clockwise direction when viewed from the left in Fig. 1, with the result that the pinion 2 will rotate in the same direction when it has meshed with the fly-wheel. 85 This is also, of course, the direction of the slight partial rotation of the pinion which occurs when the pinion is stopped momentarily in its longitudinal movement by the failure of the same to register accurately 90 with the fly-wheel. The chamfering on this particular side of the pinion teeth has a tendency to cause the necessary slight rotation of the pinion in the proper direction when the chamfered surface strikes the end 95 of the fly-wheel teeth, thereby facilitating the 100 rotary movement of the pinion for proper

meshing. If both sides of the pinion teeth should be thus chamfered, there would be some occasions when the chamfering on that side of the teeth which are straight or unchamfered in the present instance would have a tendency to rotate the pinion slightly in the reversed direction, that is, contrary to its normal and proper direction of rotation, and as a stoppage of the pinion causes the screw-shaft to rotate the pinion in unison therewith, the result would be a greater pressure brought upon the engaging portions of the teeth of the pinion and the fly-wheel.

As clearly shown in the drawing, the teeth 15 2^a of the pinion have a chamfer 2^b on one side, the other side being substantially straight, the extreme ends of the teeth at their corners are curved as shown at 2^c , the teeth having a straight portion 2^d extending 20 substantially slightly beyond the pitch line thereof and there merging into said curved or arc-shaped portion 2^e . In addition, as shown in Fig. 4, the corners of these ends of the teeth are rounded, but the extreme 25 end portions are somewhat blunt. As a result, the teeth of the pinion and fly-wheel will be brought into mesh without injury thereto and practically without any chiseling action of the pinion teeth upon the fly- 30 wheel teeth. It is obvious that in case the register between the teeth of the pinion and fly-wheel is only partial, the end of the teeth of the pinion will strike and bear along one side of the fly-wheel teeth. This described 35 formation of the end of the pinion teeth will prevent any wedging and binding action of the engaging teeth, and any abrasion or chiseling of the fly-wheel teeth, thereby permitting the engaging surfaces to move 40 smoothly and without injury upon each other.

This peculiar formation or chamfering of the engaging ends of the pinion teeth assisted by the yielding longitudinal movement of the screw-shaft permits of the use 45 of unchamfered teeth on the fly-wheel and permits of the use of cast iron fly wheels which are more economical. As shown by Figs. 1 and 5, the engaged ends of the fly- 50 wheel teeth are flat, that is unchamfered, and the construction of the parts is such that the pinion will readily and properly mesh with the fly-wheel gear even when there is an initial contact of the teeth end to 55 end, the longitudinal yielding movement of the shaft assisting in the meshing operation under such conditions inasmuch as the pinion starts its meshing operation during the time of the yielding action of the screw 60 shaft, thereby preventing any possible jamming of the pinion against the fly-wheel gear.

I claim:

1. In an engine starter transmission or 65 drive, the combination of a rotatable mem-

ber, and a pinion actuated thereby to move longitudinally thereof into engagement with a wheel of the engine to be started, and rotarily therewith, the teeth of the pinion being chamfered at their engaging end and on 70 only the side opposite its driving side, such chamfered ends being curved.

2. In an engine starter transmission or drive, the combination of a rotatable member, and a pinion actuated thereby to move 75 longitudinally thereof into engagement with a wheel of the engine to be started, and rotarily therewith, the teeth of the pinion being chamfered at their engaging end and on 80 only the side opposite its driving side, such chamfered ends being straight substantially to a point corresponding with the pitch line and curved therebeyond.

3. In an engine starter transmission or drive, the combination of a rotatable member, and a pinion actuated thereby to move 85 longitudinally thereof into engagement with a wheel of the engine to be started, and rotarily therewith, the teeth of the pinion being chamfered at their engaging end and on 90 only the side opposite its driving side, the extreme chamfered ends of such teeth being rounded.

4. In an engine starter transmission or drive, the combination of a rotatable member, and a pinion actuated thereby to move 95 longitudinally thereof into engagement with a wheel of the engine to be started, and rotarily therewith, the teeth of the pinion being chamfered at their engaging end and on 100 only the side opposite its driving side, such chamfered ends being straight substantially to a point corresponding with the pitch line and curved therebeyond, and such ends being also rounded.

5. In an engine starter transmission or drive, the combination of a rotatable member, and a pinion actuated thereby to move 110 longitudinally thereof into engagement with a wheel of the engine to be started, and rotarily therewith, the teeth of the pinion being chamfered at their engaging end and on 115 only the side opposite its driving side, such chamfered ends being straight substantially to a point corresponding with the pitch line and curved therebeyond, and the corners of such ends of the teeth being rounded with a somewhat blunt portion intervening.

6. In an engine starter transmission or drive, the combination of a gear connected 120 with the engine to be started having teeth with unchamfered ends, a rotatable member, and a pinion actuated thereby to move longitudinally thereof into engagement with said gear and rotarily with such shaft, teeth 125 of the pinion being chamfered at their engaging end and on only the side opposite its driving side.

7. In an engine starter transmission or drive, the combination of a rotatable mem-

ber, and a pinion actuated thereby to move longitudinally thereof into engagement with a wheel of the engine to be started, and rotarily therewith, the teeth of the pinion being chamfered at their engaging end and on only the side opposite its driving side, said screw-shaft having a yielding endwise move- ment when the pinion teeth contact with said wheel.
